UNITED STATES PATENT OFFICE.

ALVA MCPHAILL AND HUGH MCPHAILL, OF VISALIA, CALIFORNIA.

GLARE SCREEN.

Application filed April 6, 1922. Serial No. 550,112.

To all whom it may concern:

Be it known that we, ALVA MCPHAILL and HUGH MCPHAILL, citizens of the United States, residing at Visalia, in the county of 5 Tulare, State of California, have invented a new and useful Glare Screen, of which the following is a specification.

This invention relates to wind shield attachments, and more particularly to an attachment designed to protect the operator's line of vision from the glare of light rays from lamps of approaching vehicles, or from the sun's rays.

Another object of the invention is to provide a device of this character which may be operated by the suction of the pistons working in the cylinders of the motor, novel means being provided to control the suction through the pipe connecting the engine cylinders and cylinder of the screen.

A still further object of the invention is the provision of a protector which may be applied to the usual motor vehicle construction, eliminating the necessity of making extensive alterations to apply the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a fragmental elevational view of a wind shield disclosing an attachment constructed in accordance with the present invention applied thereto.

Figure 2 is an end elevational view thereof.

Figure 3 is a sectional view through the cylinder forming a part of the structure.

Figure 4 is an elevational view of the valve, the valve housing being shown in section.

Figure 5 is a sectional view taken on the line 5—5 of Figure 4.

Referring to the drawing in detail, the reference character 5 designates a portion of a body of a vehicle, the showing illustrating that portion of the vehicle body which supports the wind shield frame 6.

The wind shield is designated by the reference character 7, the protector being shown

as supported adjacent to the upper edge thereof.

The attachment embodies a tubular member 8 which carries hook members 9 adapted to fit over the frame of the upper section of a wind shield as clearly shown by Figure 1 of the drawing. Within this tubular member 8 is positioned the screening member 10 or guard, which is in the form of a curtain constructed of a suitable translucent material and designed to be wound on the roller 11 which is spring controlled, to return the curtain or guard to its normal position within the tubular member 8.

Disposed adjacent to one end of the tubular member 8 is a vertically disposed cylinder 12 which has its upper end secured to one end of the tubular member 8 in any well known manner. Operating within the cylinder 12 is a piston 13 which has connection 73 with the flexible member 14 that has one end thereof connected to the curtain or guard 10, the intermediate portion operating over the pulleys 15. Conveniently located on the floor of the vehicle is a valve housing 16 80 which has communication with the cylinder 12 through the pipe 17, the valve housing also having communication with the intake manifold of the internal combustion engine not shown, as through the pipe 18, whereupon the suction created by the pistons moving within their cylinders will establish a vacuum within the pipe 17 to the end that the piston 13 is moved to the upper extremity of the cylinder 12, moving the curtain or bar 90 10 to its lowermost position to guard the line of vision of the operator.

This valve housing 16 is formed with an exhaust opening 19, whereupon when the valve member 20 is in its normal position, 95 air may enter the pipe 17 to relieve the vacuum within the cylinder 12, to the end that the coiled spring, not shown, but which forms a part of the roller 11, will return the curtain or guard, to a position within the tubular member 8.

As shown, the valve member 20 is formed with a circumferential groove 21 formed adjacent to the lower end thereof, which groove is adapted to register with the pipes 17 and 18 respectively, to establish communication between the intake manifold of the engine not shown, and pipes 17 as before stated.

It might be further stated that as the plunger or valve member 20 is moved down- 110

wardly to establish communication between pipes 15 and 17, one portion of the valve member 20 moves over the opening 19 to close the same. A coiled spring is interposed 5 between the bottom wall of the valve housing 16 and the base of the valve member 20, the spring being indicated at 21. This 10 spring it will be seen normally urges the valve member 20 to the limit of its uppermost position, to the end that the vacuum within pipe 17 is normally relieved.

When the operator desires to cause the guard or screen 10 to move to its active position, it is only necessary to force the valve 15 member 20 downwardly to establish communication between the pipes 18 and 17 as described.

Having thus described the invention, what is claimed as new is:—

- 20 1. A windshield wiper including a housing, means for positioning the housing over the upper edge of a windshield, a cylinder supported adjacent to the housing, a piston movable in the cylinder, a curtain adapted 25 to be wound within the housing, flexible means for connecting the curtain and piston, whereby movement of the piston results in a relative movement of the curtain, to move the curtain with respect to the windshield, a 30 pipe having communication with the cylinder, and a valve member for controlling the passage of air to and from the cylinder.

2. A movable screen for windshields including a cylinder, suction controlled means movable within the cylinder for moving the screen to its active position, a valve housing, a pipe establishing communication between the valve housing and cylinder, said valve housing having an exhaust opening, an intake pipe extending into the valve 40 housing at a point in direct alinement with the first mentioned pipe, a vertically movable valve member having a circumferential groove adapted to normally register with the exhaust opening, said valve member 45 adapted to be moved to provide communication between the inlet pipe and first mentioned pipe, and simultaneously cut off the exhaust opening and a coiled spring for normally urging the valve member to its 50 inactive position.

In testimony that we claim the foregoing as our own, we have hereto affixed our signatures in the presence of two witnesses.

ALVA McPHAILL.
HUGH McPHAILL.
